(57) **CLAIM**

We claim the ornamental design for a portable power source, as shown and described.

DESCRIPTION

FIG. 1 is a front elevational view of a portable power source, showing our new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a perspective view thereof; and,

FIG. 8 is another perspective view thereof.

The broken lines in the drawings illustrate portions of the portable power source that form no part of the claimed design.
